UNITED STATES PATENT OFFICE.

WILLIAM BIRD DALE, OF WINNETKA, ILLINOIS, ASSIGNOR TO STREET & KENT MFG. CO., OF CHICAGO, ILLINOIS, A CORPORATION OF ILLINOIS.

COMPRESSION SHAMPOO FIXTURE.

Application filed January 21, 1924. Serial No. 687,481.

To all whom it may concern:

Be it known that I, WILLIAM BIRD DALE, a citizen of the United States, and a resident of the city of Winnetka, in the county 5 of Cook and State of Illinois, have invented certain new and useful Improvements in a Compression Shampoo Fixture; and I hereby declare that the following is a full, clear, and exact description of the same, 10 reference being had to the accompanying drawings, and to the numerals of reference marked thereon, which form a part of this specification.

This invention relates to an improved 15 form of combination basin and shampoo cocks for bathrooms, barber shops, and the like, wherein the basin fixture is used both as a lavatory and a sprinkler for shampoos.

20 It is an object of this invention to provide an improved fixture of the class described that will be more easily operated by the user or attendant with less liability of accidental injury to the head of the user 25 from contact with the valve handles.

It is a further object of this invention to provide a combined angle and elbow 30 valve or cock for a shampoo fixture whereby the operating handles of the shampoo and basin cocks will be aligned so that the user will have no difficulty in locating either handle even if blinded by soap in his eyes.

Other and further important objects of 35 this invention will be apparent from the disclosures in the specification and the accompanying drawings.

This invention (in a preferred form) is illustrated in the drawings and herein-after more fully described.

40 On the drawings:

Figure 1 is a top plan view of a fixture embodying the features of this invention.

Figure 2 is a front elevation thereof.

45 Figure 3 is an enlarged sectional detail of the elbow-angle valve shown in the other figures.

As shown on the drawings:

The reference numeral 10 is applied in 50 Figure 2 to a line representing the top surface of a wash basin through which the "stems of a pair of basin cocks" project and are connected to sources of hot and cold water supply. The basin cocks as shown are provided with compression

valves and levers 13 which do not obstruct 55 the passage of water to the shampoo fixtures thereabove through the nipples 14. An elbow-angle valve 15, to be hereinafter described in detail, is screwed onto the nipple 14, and long nipples 16 are screwed 60 into the horizontal branches 17 of these valves, meeting in a central coupling fixture 18, carrying a hose outlet 19 for the shampoo spray and a bracket 20 to support the spray head when not in use. 65

The elbow-angle valve 15 includes a dependent boss 21 to screw onto the nipple 14 and serve as a water inlet to a chamber 22 within the valve which is partitioned off from the horizontal branch 17 as at 23 in 70 Figure 3; a stepped valve seat 24 being indicated in the partition. The valve body 15 extends outwardly, at an acute instead of right angle with the plane of the piping as a whole, to contain the valve stem 25 and valve disc 26 which seats within the stepped valve seat 24. When this valve disc 26 is retracted the water passes to the sprayer through a passage 27 cored between the partition and the wall of the 80 valve.

The angle of the valve stem relative to the branch 17 is preferably such that it is aligned with the lower basis cock lever and a hand wheel 28 is provided therefor to 85 readily distinguish between the two valves by the sense of touch. One of the advantages of the aligned valve stems, due to the angle-elbow feature of the shampoo valve, is that the handle of the latter is removed from a position wherein the user is liable to bump his head against it, into a position much more accessible to a person bending over the basin while washing his hair. In such a position the valves are 90 not visible and if the person looks up to locate them he is liable to have soapy water run into his eyes.

I am aware that many changes may be made, and numerous details of construction 100 may be varied through a wide range without departing from the principles of this invention, and I therefore do not purpose limiting the patent granted hereon, otherwise than necessitated by the prior art. 105

I claim as my invention:

1. In a shampoo fixture, hot and cold water basin cocks, water supply pipes ex-

tending vertically therefrom, angle elbow valves thereabove having valve stems aligned with those of the basin cocks and a spray connection joining the outlet ends ⁵ of said valves.

2. In a shampoo fixture, compression basin cocks for hot and cold water supply, bypasses therein, nipples connected to said bypasses, elbow valves thereon, a spray ¹⁰ connection between said elbow valves, and angularly disposed valve stems for said

elbow valves aligned with the valve stems of said basin cocks.

3. In a shampoo fixture, basin cocks, angle elbow valves connected thereabove ¹⁵ having valve stems aligned with the valve stems of said basin cocks and a shampoo discharge connection between said elbow valves.

In testimony whereof I have hereunto ²⁰ subscribed my name.

WILLIAM BIRD DALE.
